UNITED STATES PATENT OFFICE.

DAVID ROUSSEAU, OF NEW YORK, N. Y.

AUTOMATIC CIRCUIT-OPENER.

SPECIFICATION forming part of Letters Patent No. 279,107, dated June 5, 1883.

Application filed April 29, 1881. (No model.)

To all whom it may concern:

Be it known that I, DAVID ROUSSEAU, of New York city, New York, have invented certain new and useful Improvements in Automatic Circuit-Openers, of which the following is a specification.

My invention applies more particularly to electric circuits for electric gas-lighting burners, but also applies to circuits for burglar-
10 alarms, railway-signals, or other similar circuits containing a number of devices which are occasionally thrown into action by the closing of the circuit.

The object of my invention is to prevent a
15 too long continued closing of the circuit, such as would occur undesignedly by a "grounding" or short-circuiting of the wires or connections at some point, and thus result in an exhaustion of the battery, so as to render the whole circuit
20 inoperative when its action might be most required; and it consists in the arrangement and combinations of parts hereinafter described, and more particularly pointed out in the claims.

The figure in the drawing represents a safety-
25 circuit for gas-lighting burners arranged according to my invention, most of the parts being shown out of proportion, and some of them represented diagrammatically for convenience of illustration.

30 In this figure, *a* indicates the source of electricity, or battery, and *b* one of the gas-burners on the gas-pipes of the house. This gas-burner is provided with movable engaging and disengaging electrodes, in the usual manner, for
35 momentarily closing and breaking the circuit, so as to produce an igniting-spark to light the gas. The circuit-wires from the battery are connected with the burner in the usual way—that is, one connects directly with the gas-pipe,
40 and is hence in connection with the movable electrode *c*, while the other wire connects to the yielding electrode *d*, which is insulated from the burner.

In the drawing the electrodes are shown in
45 contact, and the circuit hence closed, the hand being supposed to be just moving the electrode *c* for the purpose of producing an igniting-spark to light the gas, which will be effected as soon as the electrode is moved a little beyond the point shown, so as to break contact with the other electrode, and thus produce a

spark in the issuing gas-jet. After thus breaking contact and producing the igniting-spark, both electrodes retreat from the burner and remain out of contact, which is their position 55 of repose, the circuit being of course closed only momentarily for the purpose of lighting the gas. It may sometimes happen, however, owing to some entanglement of wires, crossing of connections, injury to the burner or the 60 electrodes thereon, or other accidents, that the circuit becomes undesignedly closed, and may so continue for a long time unknown to the owner, so that the battery might become grounded or exhausted, and thus the whole 65 circuit become inoperative before the fact would be known, so that the gas could not be lighted when desired; and, furthermore, electric bells or burglar-alarms in circuit with the same battery would be rendered inactive and useless 70 when their action might be called for. To prevent this is the object of my invention, which I accomplish by automatically breaking the circuit whenever it becomes closed longer than is necessary to operate any of the usual 75 devices in circuit.

Now, *A* indicates an annunciator and automatic circuit-breaker, which acts to break the circuit and indicate the fact in case the circuit should become closed by some defect for too 80 long a time, and forms one of the main parts of my invention.

B indicates a large coil, introduced in the general circuit as usually employed in gas-burner circuits, to give a strong reaction when 85 the circuit is broken at the gas-burners, so as to emit a more powerful igniting-spark. In my system, however, I provide the coil with an iron core and arrange a movable armature *e*, in operative relation therewith, thus forming an electro-magnet which, when the circuit is closed, attracts said armature *e*. Adjacent to this is arranged a strong double clock-movement, *C*, having both time and striking trains, on the ordinary plan, as indicated. The time-train terminates, of course, in an escapement, *f*, as indicated, and one of the spindles of this train is provided with a ratchet-wheel, *g*.

Now, *h* indicates a lever pivoted between the two trains, at *h*, with one arm arranged to 100 lift the detent-hooks *m* of the striking-train, while the other arm connects to a bar, *i*, which

has a pawl-tooth about midway to match with the teeth of the ratchet-wheel g , and is connected at its outer end by a spring or wire with the armature c . A second spring or wire, 5 k , extends from the armature to the clock-movement, and is provided with a hook or bend, l , which approaches the escapement-rod. The arrangement is hence such that when the circuit is closed the armature is attracted and 10 the hook l withdrawn from the escapement-rod, allowing it to swing, and hence permitting the time-train to slowly revolve. At the same moment the bar i will be raised, bringing its pawl-tooth into engagement with the ratchet-wheel g . 15 Now, if the circuit remain closed momentarily only, as will be the case if the gas is lighted at one of the burners, the armature c will be quickly attracted and retracted, and the bar i will retreat from the ratchet g , and the hook 20 l will return against the escapement, thus stopping the motion of the train after the escape of a few teeth, and causing the whole apparatus to drop again into repose. If, however, the circuit continues closed for any abnormal 25 time, the train will continue to revolve slowly, and the ratchet-wheel g will press the bar i onward, move the lever h , raise the detents m of the striking-train, and thus release this train, which will at once revolve and move a small 30 eccentric, n , one revolution, after which the detents will automatically catch the wheels in the position from which they were started, in the manner of an ordinary clock-movement; but the movement already given to the eccentric 35 n acts to throw the device A into action, which then breaks the circuit, and thus prevents any exhaustion of the battery, as will be now described. In this device A, o indicates an ordinary annunciator-magnet, over 40 which is mounted an annunciator-tag, o' , having two faces at right angles, according to a patent just granted me, and pivoted at the intersection of the angle on radial arms p , which straddle the magnet and swing on trunnions r , 45 projecting from the forked magnet-holder s . The armature t of this magnet acts, when retracted, as a pawl to uphold the tag in its quiescent position, with the normal face before the transparent opening in the surrounding 50 case, and when attracted by the circuiting of the magnet the tag is allowed to drop, so that its announcing-face comes before the transparent opening, and thus announces the fact. Now, the magnet-holder s is metallic, 55 but is attached to a supporting cross-bar, u , of wood or insulating material, as indicated, and secured to the ends of this bar are metal standards v , in which a small rock-shaft, w , is journaled. A small lever, x , projects from this 60 rock-shaft, and is engaged with the end of the eccentric-rod, which extends from the clock-movement, as before described. From the rock-shaft projects a pin, w' , which normally, or when the parts are in repose, contacts with 65 a hooked spring, y , rising from the magnet-holder. Now, the circuit-wires connect one to

the metal standard v and the other to the fixed end of a broad light plate-spring, z , which contacts at its free end with a pin projecting from the pivotal arm of the annunciator-tag 70 when said tag is in its raised quiescent position, as illustrated. It will hence be seen that the circuit is completed through the standard v , rock-shaft w , hook y , magnet-holder, tag-arm, and spring z . Now, the coil of the magnet 75 o connects at one end to the magnet-holder s and at the other end to the standard v , and hence the magnet is thus situated in a shunt of the general circuit, so that when the general circuit is closed little or no electricity 80 passes through the shunted magnet, or rather not enough to magnetize it sufficiently to attract its armature and drop the annunciator-tag. When, however, the general circuit remains closed sufficiently long to operate the 85 clock-work train and rotate the eccentric n , as before described, the movement of the eccentric-rod will tilt the lever x , turn the rock-shaft w , and cause its pin to break contact with the contact-spring y , thus breaking the usual path 90 of the current and throwing the formerly shunted magnet into full circuit, which magnet now instantly attracts its armature and drops the tag. Now, as the circuit is always completed through the spring z and pin p' , it 95 will be seen that when the tag is dropped these parts separate and instantly break the circuit, preventing any continued action of the battery; and at the same time the fall of the announcing-face of the tag before the window 100 of the annunciator gives notice of the inactive condition of the circuit, so that the circuit may be examined for the defect and the same remedied before any damage could result.

The described devices thus form an automatic monitor which always guards the circuit, so that whenever it remains closed longer than a normal interval—such as would be caused by some short circuit or other accident to the connections—this monitor then positively breaks the circuit, and at the same time gives notice of the fact, which renders this mechanism an important adjunct to such circuits. 110

If after the tag is dropped the attendant 115 wishes to prove that the circuit is defective, he simply draws out the raiser-knob a' , which again raises the tag and closes the circuit. After a certain interval the devices will go through their motions already described, and 120 the tag will be again dropped and the circuit broken, and this will be repeated as often as the tag is raised. When, however, the defect in the circuit is found and corrected, the tag is finally raised by pulling the raiser-knob, 125 and so left, as will be understood.

This safety mechanism is of course specially applicable to gas-burner circuits, but not confined thereto, as already stated, and in gas-burner circuits each burner or section or series 130 of burners will of course be connected with and represented by a distinct magnet, o , in the

annunciator-case, as will be readily understood. In the drawing only one of such series is shown, as it is only necessary to duplicate this to extend the system to as many burners as may be required.

For several reasons I prefer the clock-work mechanism shown in connection with the magnet B and armature e, to act by a long-continued closing of the circuit to throw the magnet o into full circuit; but any other device acting in the same way may be employed without departing from the principle of my invention.

In some cases the clock-work motor, in connection with the magnet B and its armature, may act to directly break the general circuit without the intervention of the device A. In this case the circuit may be completed, as indicated by dotted lines, through two tongues, 2 3, one of which is held in contact with the other by a pin on the lever h, while the lever is in its normal position. When, however, the lever is moved forward by the continued movement of the clock-work when released by a prolonged attraction of the armature e, as already described, the under tongue will be left unsupported and allowed to spring away from the upper one, thus breaking the circuit and leaving it broken. Another arrangement of similar tongues, 4 5, shown on the right of the motor may be used instead of the first named, these tongues, as will be understood, being separated by the motion of the eccentric n when the striking-train is released.

What I claim is—

35 1. The combination, with an electric generator and an electric circuit emanating therefrom, of an electro-motive device which is vitalized by the closing of said circuit, automatic time mechanism which is started into operation by said electro-motive device when so vitalized, and an automatic circuit-breaker which is operated by said time mechanism to permanently break said circuit at the expiration of a predetermined time after the closing 45 of the same, substantially as set forth.

2. An electric circuit of the kind described, provided with an electro-magnet arranged therein, in combination with a clock-work motor arranged, when released, to work a contact-

breaker to permanently break the circuit, and 50 having the said magnet arranged to thus release the said clock-work whenever said magnet remains active and the circuit remains closed longer than a normal period, substantially as herein set forth.

3. In an electric circuit for gas-lighters or equivalent devices, the combination, with an annunciator-magnet and with its indicating drop or tag, of electrical contacts operatively connected with said drop and controlling an 60 operative part of the circuit, together with means, substantially such as described, whereby the prolonged closing of the general circuit will actuate said magnet and cause it to release its tag, and thereby separate the said contacts 65 and break the circuit controlled thereby after a predetermined interval, and at the same time indicate the fact, substantially as herein set forth.

4. In a circuit for electric gas-lighters, or its 70 equivalent, the combination, with one or more gas-burners and a general electric circuit completed through the electrodes on said burners, of a main contact in said general circuit and an electro-motive device in said circuit, substantially such as described, acting to open said main contact and thus break the general circuit whenever the circuit becomes closed longer than a normal period, with a distinct annunciator-magnet for each burner or group of 80 burners, connected with the respective burners and with the general circuit in a shunt around the main contact, and with a minor contact in said shunt, which is closed when the tag of the magnet is raised or set, whereby the 85 opening of the main contact will divert or concentrate the main current into the shunt corresponding to the burner at which the circuit is closed, and thereby energize that particular magnet and cause it to release its tag, and thereby open its minor contact, and thus permanently break the defective portion of the circuit and announce the fact at the same time, substantially as herein shown and described.

DAVID ROUSSEAU.
